UNITED STATES PATENT OFFICE.

CHARLES E. MORRIS, OF LEAVENWORTH, KANSAS, ASSIGNOR TO CHARLES W. PARKER,
OF LEAVENWORTH, KANSAS.

CENTRIFUGAL GUN.

1,320,779.

Specification of Letters Patent. Patented Nov. 4, 1919.

Application filed July 17, 1916. Serial No. 109,665.

To all whom it may concern:

Be it known that I, CHARLES E. MORRIS, a citizen of the United States, residing at Leavenworth, in the county of Leavenworth 5 and State of Kansas, have invented a certain new and useful Improvement in Centrifugal Guns, of which the following is a specification.

The object of my invention is to provide 10 a novel gun which will throw a projectile accurately and with great force, which will be automatically charged, which may be readily controlled by an operator located at a distance from the gun, and in which the 15 angle of fire may be adjusted at the will of the operator.

My invention provides further novel 20 means for collecting the projectiles which have been discharged from the gun and re- turning them to the magazine of the gun.

My invention provides further a novel es- 25 capement mechanism controllable at a dis- tance by the operator for releasing the projectiles one by one from the magazine for discharge into the barrel of the gun.

My invention provides still further a novel barrel arranged to receive the projectiles from the magazine and any time 30 during the revolution of the barrel.

My invention provides still further novel 35 means controllable by the operator for holding a projectile in the barrel until such time as the gun is to be fired.

My invention also provides novel means 40 for reducing the speed of the projectile through the barrel and up to the point of its detention in the barrel where it remains until released by operation of the detent mechanism.

My invention provides still further novel 45 means for adjustably controlling the time of discharge of the projectile relatively to the position of the gun in its revolution.

Other novel features of my invention are 50 hereinafter fully described and claimed.

In the accompanying drawings, which 55 illustrate the preferred embodiment of my invention, and a modification of the gun barrel,

Figure 1 is a view of my apparatus partly 60 in side elevation, partly in vertical section and partly broken away.

Fig. 2 is an elevation of the apparatus, 55 partly broken away, looking at the side op- posite to that shown in Fig. 1, and showing a projectile in the barrel ready to be dis- charged.

Fig. 3 is a view partly in side elevation 60 and partly in vertical section of a modified form of gun barrel having a spiral projectile channel.

Fig. 4 is a front elevation of a portion of 65 the apparatus, some of the parts being broken away, and some in cross section.

Fig. 5 is a cross section on the line 5—5 70 of Fig. 2.

Fig. 6 is a horizontal sectional view on the line 6—6 of Fig. 4.

Fig. 7 is a longitudinal sectional view on 75 the line 7—7 of Fig. 4.

Fig. 8 is a transverse sectional view on the line 8—8 of Fig. 2.

Fig. 9 is a vertical sectional view, en- 80 larged, on the line 9—9 of Fig. 4.

Fig. 10 is an enlarged cross section on the 85 line 10—10 of Fig. 4.

Fig. 11 is an enlarged vertical sectional 90 view of the escapement mechanism, a por- tion of the magazine, and parts connected therewith.

Fig. 12 is a top view of what is shown in 95 Fig. 11.

Similar reference characters designate 100 similar parts in the different views.

1 designates a supporting frame of any 85 desired form and construction and which has rotatably mounted in it a transverse hori- zontal shaft 2, which is driven by any suit- able means, such as an electric motor 3 hav- ing a pulley 4 secured to an armature shaft 90 5, a belt 6 being mounted on the pulley 4 and on a pulley 7, the latter being secured rig- idly to the rotary shaft 2.

Secured to and revoluble with the shaft 95 is a barrel, comprising, in the preferred form of my invention, shown in Figs. 1, 2, 7 and 8, a substantially circular receiving chamber 8, which is centrally secured rigidly to the shaft 2, and which communicates periph- erally with a radial tubular portion 9, into 100 which the projectiles which may be balls 10, are consecutively discharged from the cham- ber 8.

As shown in Fig. 8, one end of the cham-

ber 8 is normally closed by a stationary cover plate 11 which is rigidly secured to the frame 1 and which has an opening 12 which connects the chamber 8 with a U-shaped 5 tubular magazine 13, the upper end of which is open and so disposed as to receive projectiles delivered therein by a conveyer comprising an endless inclined belt 14 having a series of transverse blades 15, Figs. 1 and 10 2, adapted to engage and carry upwardly the projectile balls 10, as the latter are delivered by an inclined chute 16 to a point at the lower end of said chute and in the path of the blades 15.

15 The chute 16 is disposed transversely to the line of fire of the barrel 9, and the ground 17 is inclined toward and at its lowermost portion is flush with the forward side of the chute 16, so that projectiles falling upon 20 said ground 17 will roll into the chute 16, and in rolling down the chute will reach the point where they will be consecutively engaged by the blades 15 of the conveyer and by said blades delivered into the upper end 25 of the magazine 13 over a semi-circular plate 18, Fig. 2, having its open side laterally disposed so that the projectiles 10, when the magazine 13 is filled, will be discharged laterally at the outer side of the magazine.

30 The belt 14 is mounted on two pulleys 19 and 20 which are rotatably mounted on a frame work 21, by means of two transverse shafts 22 and 23 respectively.

The shafts 22 and 23 are rotatably mounted 35 respectively in the upper and lower ends of the frame work 21, which frame work is supported by the frame 1.

Secured to the shaft 23 is a pulley 24 connected by a belt 25 with a pulley 26 secured 40 to the shaft 2. By this means, the conveyer is driven when the shaft 2 is rotated.

45 Releasable detent means is provided in the barrel 9 for holding the projectile 10 from being discharged from the barrel until such time as the detent means is operated to release the projectile. Said detent means comprises preferably a pivoted detent member 27 which is pivoted to the barrel 9 by a transverse pin 28, the barrel having a longitudinal slot 29, into which the detent member 50 27 may pass when released.

55 For holding the detent member 27 in the inwardly and outwardly extending position shown in Fig. 7, there is provided a bell crank lever, one arm 30 of which is adapted to be swung against the outer side of the detent member 27 so as to force the latter to the holding position shown in Figs. 2 and 7.

60 The bell crank lever is pivoted at its angle 31 to the outer side of the barrel 9 and its other arm 32, Fig. 1 has pivoted to it one end of a longitudinal rod 33, the other end of which is pivoted to one arm 65 34 of a bell crank lever pivoted at its

angle by a pin 35 to the outer side of the chamber 8. The other arm 36 of said bell crank lever is adapted to be struck and swung by a cam 37, Fig. 9, which is provided on the periphery of a sleeve 38 which 70 is slidable longitudinally on a cylindrical bearing 39, Fig. 8, in which the shaft 2 is rotatably mounted. The sleeve 38 with its cam 37 is movable to and from a position in which the cam 37 will be in the path of movement of the arm 36 of the adjacent bell crank lever, thereby swinging said lever and its arm 34 so as to release the detent member 27, through the intermediacy of the rod 33 and bell crank arms 32 and 30. 80

For returning the detent means to the holding position, there is provided a coil spring 40, Fig. 1, which is attached to the barrel 9 and to the rod 33 in a manner such as to normally force the rod 33 longitudinally outwardly.

When the sleeve 38 is forced against the chamber 8, so that the cam 37 is in the path of the bell crank lever arm 36, and the barrel is revolving with the shaft 2, the cam will 90 swing said lever so as to release the detent member 27 once during each revolution of the barrel 9 on its axis.

In order that the point of contact or time of contact of the cam 37 with the arm 36 may be changed, so that the detent member 27 may be released at different angles of the barrel 9, the sleeve 38 is circumferentially adjustable within predetermined limits by means of the following described mechanism. 95 The sleeve 38 is provided with a radial arm 41 to which is pivoted one end of a horizontal bar 42, Fig. 10, the other end of which is pivoted to a vertical bar 43, which, intermediate of its ends, is pivoted by a pin 44 to the frame work 1. The lower end of the bar 43 is pivoted to the rear end of a forwardly extending rod 45, Fig. 1, the forward end of which is pivoted to the lower end of a lever 46, which is pivoted by a pin 47 to a piston 110 frame 48.

The lever 46 is locked in the position to which it may be adjusted by an arcuate toothed plate 49 which is adapted to be engaged by a sliding bolt 50 connected by a rod 51 with a bell crank lever 52 pivoted to the lever 46 adjacent to the upper end thereof.

By throwing the lever 46 so as to draw the rod 45 forwardly, the sleeve and cam 38 and 37 respectively are turned clockwise, as viewed in Fig. 1, so as to sooner have the cam engage the bell crank lever arm 36, thereby releasing the detent member 27 when the barrel 9 is at a greater angle to the horizontal than when the lever 46 is swung in the opposite direction.

If desired, such retraction of the lever 46 in the opposite direction may be effected by a coil spring 53, Fig. 1, one end of which 130

is secured to the frame 1 and the other end of which is secured to the bar 43 above the pin 44.

Thus by swinging the lever 46 to different 5 positions, the angle at which the gun is fired may be varied to suit the operator.

For moving the sleeve 38 longitudinally into and out of the operative position, I provide a vertical bar 54, which is pivoted intermediate of its ends by a horizontal pin 55 to the frame 1.

The lower end of the bar 54 is secured to one end of a coil spring 56, Fig. 4 and Fig. 6, the other end of which is secured to the frame 1 in a manner such that the spring 56 will normally swing the bar 54 so as to move the upper end of the said bar outwardly.

The upper end of the bar 54 is provided 20 with two arms 57 respectively provided with inwardly extending pins 58 which are respectively mounted in slots 59 provided in diametrically opposite sides of the sleeve 38.

In order that the upper end of the bar 54 25 may be swung inwardly, a horizontally disposed bell crank lever, which is pivoted by means of a vertical pin 60 to the frame 1, has one of its arms 61 mounted in a transverse hole provided therefor in the bar 54 adjacent to the lower end thereof, as shown 30 in Figs. 4 and 6. The other arm 62 of said bell crank lever is attached to one end of a horizontal longitudinally disposed coil spring 63, Fig. 6, the forward end of which 35 is attached to a longitudinally movable horizontal bar 64, the forward end of which is pivoted to the lower end of a lever 65, which is pivoted to the frame 48.

By throwing the upper end of the lever 40 65 rearwardly, that is toward the frame 1, the bar 64 is drawn forwardly and by means of the spring 63 and bell crank lever 62, will swing inwardly the upper end of the bar 54, thereby sliding the sleeve 38 to a position 45 in which the cam 37 will be in the path of the bell crank lever arm 36, so that when said arm strikes the cam, the detent member 27 will be released and the projectile 10 held thereby will also be released and will be 50 projected by centrifugal force from the barrel 9.

In order that the projectiles 10 may be fed one by one at the proper time from the magazine 13 into the chamber 8, I provide 55 the following described escapement mechanism.

Referring now particularly to Figs. 2, 4, 6, 11 and 12, 66 designates a horizontal rock shaft which is pivotally mounted in two 60 arms 67 of a metal loop which is vertically disposed and embraces and is secured to the two arms of the magazine 13. Pivotally mounted on the rock shaft 66 is a collar 68 provided with a crank 69 which is pivoted 65 to the upper end of a rod 70, the lower end

of which is pivoted to an arm 71 of a bell crank lever which is pivoted by a horizontal pin 72 to the frame 1. The other arm 73 of the said lever is pivoted to the rear end of the bar 64.

Rigidly secured to the collar 68 is a crank 74 which is adapted to move from the released position, shown in solid lines in Fig. 11 through a slot 75 in the upper side of the lower arm of the magazine 13 to the position shown in dotted lines in said figure, in which latter position the crank 74 will hold the foremost projectile 10 from passing out of the magazine into the gun barrel chamber 8.

When the lever 65 has its upper end 80 swung toward the frame 1, the bar 64 will be drawn forwardly, thereby rocking the collar 68 so that the crank 74 will be thrown to the holding position shown in 85 dotted lines in Fig. 11.

Upon swinging the lever 65 in the opposite direction, the collar 68 will be rocked in the opposite direction to the position shown in solid lines in Fig. 11, thereby releasing 90 the foremost projectile 10 which will then enter the chamber 8 and will then pass, due to centrifugal force, into the barrel 9 and against the detent member 27, where it will be held until released by the operator again swinging the upper end of the 95 lever 65 toward the frame 1. Upon such swinging of the lever 65, the detent member 27 will be released through the intermediacy of the cam 37, bell crank lever 36—34, rod 100 33, and bell crank lever 32—31—30, the cam sleeve 38 being moved to the operative position through the intermediacy of the bar 54, bell crank lever 61—62, spring 63 and bar 64.

At the same time, the sleeve 68 will be rocked so that the crank 74 will pass to the position shown by dotted lines in Fig. 11, through the intermediacy of the crank 69, bar 70 and bell crank lever 71—73.

In order that, when the foremost projectile 10 in the magazine is released by the movement of the crank 74 to the position shown in solid lines in Fig. 11, due to the forward swinging of the upper end of the 115 lever 65, the next projectile 10, shown in solid lines in Fig. 11, shall be held back, the rock shaft 66 is provided with a crank arm 76, which is adapted to pass from the position shown in dotted lines in Fig. 11 to the 120 position shown in solid lines in said figure. In the latter position, the crank arm 76 will engage the projectile next to the foremost one and will hold it until the bar 70 is again moved downwardly due to the rearward 125 swinging of the upper end of the lever 65.

The collar 68 is notched to receive the crank arm 76, so that the latter may have a slight circumferential movement with the rock shaft in the collar 68. A coil spring 130

77 encircling the rock shaft 66 and secured at one end to the loop 67 has its other end bearing against the crank arm 76 in a manner such that the latter will normally be 5 held against a shoulder 78 on the collar 68. In case that the crank arm 76 should strike on top of a projectile 10, the spring 77 will yield while the collar 68 is being turned so as to raise the crank 74 to release the fore- 10 most projectile. As soon as the collar 68 is turned so as to depress the crank 74, after the foremost projectile has been released, the shoulder 78 of the collar 68 will strike the crank arm 76 and swing it upwardly 15 through the slot 75, thereby releasing the next projectile, which will then roll downwardly until it is stopped by the crank 74.

The lever 65 may be pivoted, as is the lever 46, to the pin 47.

20 The barrel may have secured to it a counter balance comprising two outwardly extending bars 79 secured to the periphery of the chamber 8 opposite to the barrel 9, and having secured to their outer ends a 25 weight 80.

For assisting in retracting the bell crank lever 71-73 and the parts connected therewith to the position shown in Fig. 2, a vertical coil spring 81 may have one end secured to the lever arm 71 and its other end secured to the frame 1.

30 For limiting the swing of the lever 34-36 against the tension of the spring 40, a stop 32 may be provided on the outer side of the 35 chamber 8.

For the purpose of preventing the projectiles pocketing in the chamber 8, and to insure their passing into the barrel 9, the inner periphery of the chamber 8 may be 40 provided with a lining 83 which gradually increases in thickness each way from the barrel 9, the thickest portion being diametrically opposite the longitudinal center of the barrel 9. The inner wall of the chamber 8 45 is thus eccentric to the shaft or axis 2, with that portion which is most distant from the axis being nearest to the inner end of the barrel 9.

In order that the projectile may not be 50 thrown too forcibly against the detent member 27, the inner wall of the barrel 9 is lined with yielding corrugated strips 84, the corrugations at opposite sides of the barrel being arranged so as to slightly shift laterally the projectile as it passes through the 55 barrel. This changing of the course of the projectile, as well as the friction against the lining strips 84 will reduce the speed of the projectile as it passes through the barrel 9 60 to the detent member 27.

In operating my invention, the motor 3 is started, thereby rotating the barrel 9 in the direction indicated by the arrow in Fig. 1. The magazine 13 is then filled with project- 65 tiles. If the lever 65 is in the position shown

in Fig. 1, the foremost projectile 10 will rest against the crank arm 76. If now the lever 65 is swung rearwardly at its upper end, the bar 64 will be forced forwardly, thus swinging downwardly the bell crank arm 71, and 70 through the intermediacy of the rod 70 and crank 69 rocking the collar 68 to the position shown in dotted lines in Fig. 11, in which position the crank arm 74 will engage and hold the foremost ball or projectile 10, the latter having been released from the crank arm 76. If now the lever 65 be swung forwardly, or to the left, as viewed in Fig. 1, the collar 68 will be rocked in the opposite direction from that in which it was first 80 rocked, thereby depressing the crank arm 76 and lifting the crank arm 74 so as to release the foremost ball or projectile, upon which the latter will roll by gravity into the chamber 8 from which it will pass, due to centrifugal force, into the barrel 9 and against the detent member 27, where it will remain until the detent member is released from the arm 32. The gun will now be in condition to be fired. The operator will now swing the 85 lever 46 so as to adjust the cam 37 to the proper position circumferentially for the angle at which the gun is to be discharged.

If now the lever 65 be swung at its upper end to the right, as viewed in Fig. 1, the 90 cam 37 will be forced into the path of the lever arm 36, through the intermediacy of the bar 64, spring 63, bell crank lever 62-61, bar 54 and sleeve 38, so that when the barrel 9 has revolved to the proper position, the detent member 27 will be released by the mechanism already described, and the projectile which has been carried in the barrel will be discharged by centrifugal force. 95

When the lever is swung to the right, as 100 above described, the collar 68 will be rocked so as to swing upwardly the crank arm 76 and downwardly the crank arm 74, thus permitting the projectile which is now foremost in the magazine to roll downwardly 105 against the arm 74. Upon then swinging the upper end of the lever 65 to the left, as viewed in Fig. 1, the collar 68 will be rocked so as to lift the arm 74, thereby releasing therefrom the foremost projectile, which 110 will now roll into the chamber 8 and into the barrel 9, where the projectile will be held by the detent member 27, the latter having been restored to the holding position by the last swinging movement of the lever. 115 The gun will now be loaded so as to be again fired at the will of the operator in the manner already described. 120

The projectiles which have been fired if falling or thrown upon the inclined ground 125 17, will roll into the inclined chute 16 and will pass therein one by one to the conveyer where they will be picked up one by one by the blades 15 and discharged thereby into the upper end of the magazine 13. If there 130

are more projectiles than the magazine will hold, the surplus ones will be discharged laterally from the semicircular plate 18.

As the range of movement of the bar 64 is greater than is required for the bar 54 in swinging the sleeve 38 to the operative position, the spring 63 is inserted between the bar 64 and the lever arm 62. The spring 63 is stronger than the spring 56 so as to 10 permit it to overcome the latter when the bar 64 moves forwardly.

In Fig. 3 is shown a modified form of barrel designed to reduce the speed of the projectile as it moves outwardly in the barrel 85, which is of involute form, and which at its outer end is provided with a radial cylindrical tubular portion 86, in which are mounted a detent member 27 and a bell crank lever 30 similar in form, mode of operation and function to the like designated elements in the other form of my invention.

In the form of my invention shown in Fig. 3, the shaft 2 to which it is secured is disposed substantially centrally, and the projectiles are fed into the barrel closely adjacent to the shaft 2. As the barrel 85 revolves, the projectiles will be caused by centrifugal force to travel outwardly through the involute barrel until they reach 30 the detent member 27, where they will rest until this member is released by mechanism already described with reference to my other form of invention. The open side of the involute barrel 85 will be normally closed 35 by a plate corresponding to the plate 11 having the opening 12 communicating with the magazine 13.

I do not limit my invention to the structures shown and described, as modifications, 40 other than shown, may be made within the scope of the appended claims, without departing from the spirit of my invention.

What I claim is:—

1. In a centrifugal gun, a continuously revolving barrel from which the projectile is discharged directly from the gun, releasable detent means for holding a projectile in the barrel adjacent to the muzzle thereof, controlling means movable to and from a position in which it will actuate said detent means to release the projectile, and manually operated means for moving said controlling means.

2. In a centrifugal gun, a continuously revolving barrel from which the projectile is discharged directly from the gun, releasable detent means for holding a projectile in the barrel adjacent to the muzzle thereof, circumferentially adjustable controlling 60 means movable to and from a position in which it will actuate said detent means to release the projectile, and manually operated means for actuating said controlling means.

3. In a centrifugal gun, a continuously

revolving barrel, releasable detent means for holding a projectile in the barrel, circumferentially adjustable controlling means movable to and from a position in which it will actuate said detent means to release the projectile, manually operated means for moving said controlling means to said position, and manually operated means for circumferentially adjusting said controlling means.

4. In a centrifugal gun, a continuously revolving barrel from which the projectile is discharged directly from the gun, releasable detent means for holding a projectile in the barrel adjacent to the muzzle thereof and revoluble with the barrel, a tripping device movable into and out of the path of movement of said detent means, and manually operated means for moving said tripping device into the path of movement of said detent means.

5. In a centrifugal gun, a continuously revolving barrel, releasable detent means revoluble with the barrel for holding a projectile in the barrel, a tripping device movable into and out of the path of movement of said detent means and circumferentially adjustable to different positions so as to change the time of engagement with the detent means relatively to the position of the barrel, and manually operated means for moving the tripping device in one direction.

6. In a centrifugal gun, a continuously revolving barrel, releasable detent means revoluble with the barrel for holding a projectile in the barrel, a tripping device circumferentially adjustable around the axis of the barrel and movable into and out of the path of movement of said detent means, manually operated means for forcing said tripping device into the path of movement of said detent means, and manually operated means for circumferentially adjusting said tripping device.

7. In a centrifugal gun, a revoluble barrel, a support on which the barrel is revoluble, detent means arranged to hold a projectile in the barrel adjacent to the muzzle thereof during the revolution thereof, and adjustable means by which the detent means may be operated to release a projectile at different points with respect to said support in the path of revolution and at every revolution of the barrel.

8. In a centrifugal gun, a revoluble barrel from which the projectile is discharged directly from the gun, detent means arranged to hold a projectile in the barrel during the revolution thereof adjacent to the muzzle of the barrel, tripping means movable into and out of the path of movement of said detent means, and means for adjusting said tripping means so as to vary its time of engagement during the revolution of the barrel with said detent means.

9. In a centrifugal gun, a revoluble barrel, a support on which the barrel is revoluble, a magazine arranged to discharge projectiles into said barrel, detent means for holding a projectile in the barrel adjacent to the muzzle thereof, means adjustable to different positions relatively to said support for operating said detent means to release the projectile in the barrel at a pre-determined point in the revolution of the barrel, and means by which the projectiles may be consecutively fed into said barrel from said magazine.
10. In a centrifugal gun, a revoluble barrel, a magazine arranged to discharge projectiles into the barrel, detent means for holding a projectile in the barrel adjacent to the muzzle thereof, an oscillatable member, and means by which when said member is moved in one direction, the detent means will be operated to release the projectile in the barrel, and when moved in the opposite direction, a projectile will be released from the magazine so as to be discharged into the barrel.
11. In a centrifugal gun, a revoluble barrel, detent means for holding a projectile in the barrel, a magazine arranged to discharge projectiles into said barrel, escapement means for consecutively releasing the projectiles so that they may feed one by one into the barrel from the magazine, tripping means movable into and out of the path of movement of said detent means, manually operated means arranged to be oscillated, means by which when the manually operated means is moved in one direction, the tripping means will be moved into the path of movement of the detent means, and means by which when the manually operated means is moved in the opposite direction, said escapement means will be operated to release a projectile from the magazine so that it may discharge into said barrel.
12. In a centrifugal gun, a revoluble barrel provided with means for deflecting the course of a projectile from a radial line as the projectile passes through the barrel.
13. In a centrifugal gun, a revoluble barrel, and a releasable detent carried thereby for holding a projectile in the barrel, the barrel being provided with means for deflecting the course of a projectile from a radial line as the projectile passes through the barrel to the detent.
14. In a centrifugal gun, a revoluble barrel, and yielding means provided in the barrel for resisting the outward movement of a projectile through the barrel.
15. In a centrifugal gun, a revoluble barrel, having yielding means for resisting the outward movement of a projectile through the barrel, and a releasable detent for holding the projectile after it has been operated upon by said yielding means.
16. In a centrifugal gun, a revoluble barrel having an axial receiving chamber, the inner wall of which is eccentric to the axis of the barrel, and provided with a radial tubular discharge portion communicating with said chamber at that portion distant from the axis.
17. In a centrifugal gun, a revoluble barrel having an axial receiving chamber, the inner wall of which is eccentric to the axis of the barrel, the barrel having a radial tubular discharge portion communicating with said chamber at that portion distant from the axis, and means by which projectiles may be fed into said chamber at any time during the revolution of the barrel.
18. In a centrifugal gun, a revoluble barrel, releasable detent means carried by said barrel for holding a projectile in the barrel, a cam tripping device slideable parallel with the axis of the barrel to and from a position in which it will engage and operate said detent means so as to release a projectile in the barrel, and circumferentially adjustable, so that the time of tripping may be changed, and means for moving said tripping device into and out of the path of movement of said detent means.
19. In a centrifugal gun, a revoluble barrel, a magazine arranged to discharge projectiles into the barrel, detent means for holding a projectile in the barrel, escapement means by which the projectiles may be released one by one from the magazine to the barrel, a lever, and means by which when the lever is swung in one direction, the detent means will be operated to release the projectile which is in the barrel, and by which when the lever is swung in the opposite direction the escapement will be operated to release a projectile to the barrel.
20. In a centrifugal gun, a revoluble barrel, releasable detent means for holding the projectile in the barrel, means for feeding projectiles one by one into said barrel, and manually controlled means connected with said detent means and said feeding means by which the detent means may be operated to release the projectile in the barrel and the feeding means then operated to discharge a projectile into the barrel.
21. In a centrifugal gun, a revoluble barrel, releasable detent means for holding a projectile in the barrel, a magazine arranged to discharge into the barrel, escapement means by which the projectiles in the magazine are fed one by one into the barrel, adjustable means for changing the angle of fire of the barrel, and manually controlled means by which the detent means and escapement means are operated to release the projectile from the barrel and to then release a projectile in the magazine so that it may be discharged into the barrel.
22. In a centrifugal gun, a revoluble bar-

rel from which the projectile is discharged directly from the gun provided with detent means adjacent to the muzzle thereof for releasably holding a projectile in the barrel, 5 and projectile feeding means having provision for feeding a projectile into the bar-

rel only at such time as the muzzle detent means is operated to release a projectile held thereby.

In testimony whereof I have signed my 10 name to this specification.

CHARLES E. MORRIS.
